(57) **CLAIM**

The ornamental design for a necklace, as shown and
described.

DESCRIPTION

FIG. 1 is a front, top perspective view of a necklace,
showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, top perspective view of the necklace in a
detached state; and,

FIG. 10 is a rear, bottom perspective view of the necklace in a
detached state.

The dashed broken lines in the figures are for the purposes
of illustrating portions of the necklace that form no part of
the claimed design.

The short-short-long dashed broken lines immediately adja-
cent to the claim area in the FIG. 10 are for the purposes of
illustrating the boundaries of the necklace, and form no part
of the claimed design.
